UNITED STATES PATENT OFFICE.

EDWARD M. BENTLEY AND WALTER H. KNIGHT, OF WASHINGTON, D. C.

ELECTRIC WAY.

SPECIFICATION forming part of Letters Patent No. 276,757, dated May 1, 1883.

Application filed March 31, 1883. (No model.)

To all whom it may concern:

Be it known that we, EDWARD M. BENTLEY and WALTER H. KNIGHT, of Washington, District of Columbia, have invented certain new and useful Improvements in Electric Ways, of which the following is a specification.

Our invention consists in a system of electric conductors forming an electric way where-
to in wires of different classes can be run in the same conduit, or within inductive proximity of one another, and still be in substantially mutual inductive independence.

In the accompanying drawings, Figure 1 is a diagram of two conductors in mutual anti-inductive relation. Fig. 2 represents a method of laying the different classes of conductors in different parts of the street. Fig. 3 shows a convenient means for introducing additional conductors. Fig. 4 is a perspective view, showing the arrangement at the junction-box. Fig. 5 shows a yielding connection between two sections of conductors. Fig. 6 illustrates by a partial perspective the mode of crossing the conductors. Fig. 7 is a side elevation, showing the manner of bringing the telephone or telegraph wires to the surface at the junction-box.

We represent herein conductors of three different classes—viz., electric-light, telephone, and telegraph conductors, the latter including fire, district, printing, and all other telegraphs, and the light-wires being also used for the transmission of power, and for other desirable purposes.

In Fig. 1, A A' represent the direct and return wires of a complete metallic circuit, preferably a light-circuit, and T T' represent neighboring conductors. A A' are situated in the same plane and cross each other at intervals, so that the positive and negative wires exchange positions, the positive wire taking up a position in a line which is a continuation of the previous section of negative wire, and vice versa. It will thus be seen that any neighboring wires, as T T', in any position parallel to A A', will be subject to equal and opposite induction, provided they pass along an even number of sections of A A'. T T' may be either telephone or telegraph wires, preferably telephone-wires, and if a third

class of wires be brought into the vicinity it will only be necessary to render them independent of T T'. This may be done by providing a common return for them, as is shown and claimed in an application filed March 27, 1883, or by inserting a metallic shield between them, as is set forth and claimed in an application of the same date. These various classes of wires may be all in the same conduit, as in said applications, and as shown in Fig. 4, or the different classes be put in different parts of the street.

In Fig. 2 the light-wires and through telegraph-wires are shown in a conduit in the middle of the street, while the telephone and local telegraph wires are at the side, just inside the curb. A light-wire is shown taken out to the side of the street from the central conduit. In any case the wires should be crossed at intervals, preferably at the junction-boxes, which are situated at convenient distances apart along the line. Fig. 4 shows such a junction-box with the light-wires crossed and the telephone-wires brought individually to a common surface at the top of the box by means of a connection-board made up of transverse sticks of wood woven in among the wires in a similar manner to that shown in one of the above-mentioned applications. The light-wires occupy the center of the conduit in a vertical line from top to bottom, the sets of positive and negative wires A and A' each emerging from the section of conduit D into the junction-box in two vertical rows on either side.

Between the two central rows, one of which, of course, is positive and the other negative wires, a square stick, B, of wood or other suitable material, is placed obliquely in the vertical plane of the conduit, from the upper to the opposite lower corner of the junction-box, and each pair of wires A A' is brought out into the box until they come to the stick B, one on each side of the stick. Each wire then takes a half-turn around the stick, (see Fig. 6,) one, A, going obliquely across the under surface of B to the edge, and then up at an angle to the edge, to the diagonally-opposite edge from which it started, and thence on in the line of direction of A'. The other wire, A', is first bent up at an angle to B, and thence obliquely across the

upper surface to the diagonally-opposite edge from which it started, and then goes on into the next section in the line of direction of wire A. At a point lower down on B the next pair 5 of wires A A' cross each other by being bent, respectively, over and under B in like manner. It will be seen that the pairs of wires will be laid over B in an orderly manner, so that they will be readily accessible and a certain distance 10 maintained between each pair of wires. For the next two rows of wires four small sticks, C, are placed parallel to B, one at a short radial distance from each corner, so that the four form a square frame inclosing B and concentric and symmetrical with it. The two outer 15 rows of wires, A A', are then bent by pairs around this skeleton stick, just as the inner rows were bent around the inner solid stick, B. When rods are used for conductors, as in 20 the present incandescent systems, it will be necessary to provide yielding connections to allow for the expansion and contraction of the rods under varying temperature. In Fig. 5, A and A' are conductors of a circuit, insulated 25 and supported in any convenient way. At points of junction these conductors cross each other, and are connected by means of the curved spring-strips E E'. These strips serve a triple function, being electrical connections 30 holding the two conductors at the proper distance apart while crossing, and also allowing for expansion and contraction of A A'. Existing systems, where connections of this kind are used, can be rendered anti-inductive to all 35 external conductors by simply crossing the connections at each junction-box, so that the positive and negative conductors occupy reversed positions in successive sections.

The manner of bringing all the wires of a system normally occupying a cross-section of two 40 dimensions to a common surface is illustrated in Figs. 4 and 7. A number of triangular sticks, F, are laid just above the wires in a horizontal plane, parallel and close to each other 45 and transverse to the line-wires. The successive wires T in each vertical row are brought up and bent, respectively, over the successive sticks F. They are then brought down again to the proper level for continuing their course 50 into the next section in a straight line, their relative horizontal position being maintained by bending them again around sticks F'. This arrangement forms a connection-board made up of transverse sticks and wires woven together, and presenting wicker-work-like 55 surface. The sticks are held in place by the wires, and all the lines are brought to the surface in a systematic way.

In Fig. 4 the telegraph-wires are shown on 60 the opposite side of the light-wires from the telephone-wires. They may be run in anti-inductive cables; or the mass of metal of the light-wires may be relied upon as an inductive shield to protect the two classes of wires from 65 each other.

We have shown the lower portion of the

space for telegraph-wires occupied by cables containing through lines. The upper part is filled or partly filled with local wires laid in insulating-strips. These may be brought up 70 to the surface like the telephone-wires, and others added as the needs of the service require.

Fig. 3 shows the most convenient way of introducing new conductors, or insulating-strips filled with conductors, or grooved for their 75 subsequent reception. The whole or part of a section, G, between two junction-boxes is left open or accessible, while the rest of the sections are permanently covered up. To put in 80 new conductors or new holders, the section G is opened, and then conducting-rods, grooved boards, or other rigid objects can be laid down in G and passed through succeeding sections, from one junction-box to another, until the entire conduit-space is filled.

It is to be understood that all matter herein shown or described but not claimed is not hereby abandoned to the public, but is reserved for future applications.

What we desire to claim in this application 90 as our invention is—

1. The combination, with an external conductor, of the direct and return conductors of an electric circuit, said direct and return conductors exchanging their lineal positions at 95 intervals.

2. The combination, with an external conductor, of a pair of inductively-opposing sections of the direct and return conductors of an electric circuit, the direct and return conductors in said sections being in the same plane.

3. The combination of the direct and return conductors of an electric circuit, said conductors crossing each other at sectional points, and each section having a corresponding inductively-opposing section in the same plane.

4. The combination of the direct and return conductors of an electric-light circuit, said conductors crossing each other at sectional points, each section being in one plane and having a 110 corresponding inductively-opposing section in the same plane.

5. In an electric way divided into longitudinal sections, the combination of the direct and return conductors of a metallic circuit and a 115 portion of another circuit, the wires all running substantially parallel throughout each section, and the direct and return conductors crossing each other at the ends of the sections, so as to interchange their lineal positions, substantially as and for the purposes set forth.

6. In an electric way divided into longitudinal sections, the combination of the direct and return conductors of a metallic circuit, crossing each other at the ends of the sections, with a portion of another circuit extending the distance of an even number of sections along the way, for the purpose set forth.

7. The combination, with a number of permanently-closed sections of an electric way, 130 separated by junction-boxes, of an open or accessible section extending between two junc-

tion-boxes for the introduction of rigid conductors or wire-holders.

8. The combination, with two electric conductors crossing each other, but not coming in contact nor in comparatively close proximity, of a separating-stick, each of the two conductors making a half-turn around the stick.

9. The combination, with a series of pairs of electric conductors, of the oblique stick B, the pairs of conductors crossing each other at successive points of the stick.

10. The combination, with stick B and conductors arranged thereon, of an external frame and conductors similarly arranged upon it.

11. The combination, with wires in layers, of transverse bars in a single surface, the successive layers of wires being looped over the successive bars, so as to be brought to the single surface.

12. The combination of wires T and bars F and F', substantially as described.

13. The combination of electric wires in a conduit in the center of the street with wires of different classes arranged at the sides of the street in anti-inductive relation to the central wires.

14. The combination of conductors A A' and curved or bent expandible crossed connectors E E', uniting the conductors of one section with the diagonally-opposite conductors of the next section.
